US00D915485S

(12) **United States Design Patent** (10) Patent No.: **US D915,485 S**
 Smith et al. (45) Date of Patent: **** Apr. 6, 2021**

(54) **TRANSMISSION REAR HOUSING**

(71) Applicant: **Eaton Cummins Automated Transmission Technologies, LLC**, Galesburg, MI (US)

(72) Inventors: **Timothy Scott Smith**, Paw Paw, MI (US); **David L. Wadas**, Kalamazoo, MI (US); **Przemyslaw Tomasz Michalski**, Gdansk (PL)

(73) Assignee: **Eaton Cummins Automated Transmission Technologies, LLC**, Galesburg, MI (US)

(**) Term: **15 Years**

(21) Appl. No.: **29/705,725**

(22) Filed: **Sep. 13, 2019**

(51) LOC (13) Cl. **15-99**

(52) U.S. Cl.

USPC **D15/149**

(58) **Field of Classification Search**

USPC D15/1-5, 148, 149

CPC F16H 15/28; F16H 15/503; F16H 37/084; F16H 2037/0886

See application file for complete search history.

(57) **CLAIM**

The ornamental design for a transmission rear housing, as shown and described.

DESCRIPTION

FIG. 1 is a front perspective view of a transmission rear housing;

FIG. 2 is a front planar view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof.

The broken lines in FIGS. 1-7 are for environmental purposes only and form no part of the claimed design.

1 Claim, 7 Drawing Sheets
